UNITED STATES PATENT OFFICE

1,964,914

CARD FEEDING DEVICE

Laurens Hammond, Chicago, Ill.

Application November 28, 1932, Serial No. 644,671

10 Claims. (Cl. 271—42)

My invention relates generally to card feeding devices and more particularly to improvements in means for mechanically removing cards successively from a stack. The invention is particularly useful in automatic playing card dealing apparatus but may also be used in other machines wherein playing cards, or similar sheets or cards, are to be mechanically separated.

It is an object of my invention to provide an improved mechanism for successively removing cards from a stack and feeding them to a position for individual handling.

A further object is to provide an improved card feeding mechanism in which means are incorporated to prevent removal of more than one card at a time from a stack.

A further object is to provide an improved card separator usable in card feeding mechanism in which means are incorporated to prevent removal of more than one card at a time from a stack.

A further object is to provide an improved card separator usable in card feeding devices and operable to disengage one card from another card or group of cards to which it may tend to adhere.

Other objects will appear from the following description, reference being had to the accompanying drawings, in which

Fig. 1 is a plan view of a card dealing apparatus in which my improved card feeding mechanism is incorporated;

Fig. 2 is a plan view of the card separating mechanism;

Fig. 3 is a vertical sectional view thereof taken on the line 3—3 of Fig. 2;

Fig. 4 is an end elevational view thereof looking in the direction indicated by the arrows 4—4 of Fig. 3;

Fig. 5 is an elevational view of the card feeding mechanism, a portion of the card feeding tray being shown in section;

Fig. 6 is a view similar to Fig. 5, illustrating the operation of the card separator, and

Fig. 7 is a view similar to Fig. 6, showing the card separator mechanism in different operative positions.

In my copending application, Serial No. 637,402, filed October 12, 1932 (which has matured into Patent No. 1,889,729, dated November 29, 1932), I have shown and claimed an improved card table with automatic dealing mechanism in which means operative successively to feed playing cards from a deck is disclosed. My present invention is an improvement upon the card feeding mechanism therein disclosed.

I have illustrated the present invention as used

in a card dealing apparatus of the type shown in my aforesaid patent. This apparatus comprises, generally, a bridge table having a square, boxlike frame 10 and bottom 12 in which is incorporated a card dealing mechanism comprising a deck receiving tray 14, a circular track 15, a plurality of card receptacles S, W, N, E, and mechanism for successively removing cards from the deck tray 14, conveying cards along the track 15 and depositing them in the pockets S, W, N, E, in a certain predetermined order.

Since the present invention relates solely to the card feeding means, reference may be had to my aforesaid patent for a detailed description of the remaining parts of the card dealing mechanism.

The card picker mechanism, or the means by which the cards are successively removed from the deck and conveyed to a position where they may be individually handled by other suitable mechanism, comprises a turntable 16 mounted for rotation about a stud 18. The turntable has an arm 20 pivotally secured thereto, a torsion spring 24 being utilized resiliently to hold a roller 26 which is mounted for free rotation upon the arm 20 adjacent its end, in contact with the inner rail 28 of the track 15. A picker thumb 30 (Figs. 1 and 5) is secured to the extremity of the arm 20 by means of a suitable clip 32.

The turntable also has a carrier arm 34 pivotally secured thereto, the end of this arm being provided with a felt covering 36 which rests upon the outer rail 38 of the track 15. The carrier arm has a pusher 40 secured thereto, the pusher carrying a flat leaf spring buffer 42 for engagement with the rearward edge of a card for propelling the latter about the track 15. The turntable 16 is rotated by a suitable motor 44.

The card tray 14 is provided with a box 46, one end of which is open, and which is adapted to receive a deck of playing cards and hold them in properly stacked position.

As best shown in Fig. 5, a movable guide 48, pivoted at 50 and normally held against a fixed stop 52 by a spring 54, forms a guide for the picker thumb 30 in its movement toward the stack of cards, the arm 48 forming an extension of the inner track 28, upon which the roller 26 may roll. By means of this guide, the picker thumb is caused to move in an inclined path (represented by the dot and dash line 56 in Fig. 5) at an acute angle of incidence with reference to the surface of the topmost card of the stack. The picker thumb is made of relatively soft rubber, or a similar material which has a high coefficient of friction with

respect to the card, and substantially at the instant when the roller 26 leaves the end of the guide 48 will engage the topmost card and move it, together with any card which may have adhered to the topmost card, against a pair of inclined rails 58, 60. The rail 58 (Figs. 2, 3 and 4) is provided with means for separating the topmost card from any lower cards which may have adhered thereto and thus have been displaced from the stack. This means comprises a card separator 62 which is pivoted at 64 to a bracket 66, the bracket being secured to the rail 58 by a rivet 68. The card separator 62 is capable of pivotal movement between a sidewardly bent stop lug 70 formed on the bracket 66 and a similar lug 72 likewise formed integrally with the bracket 66 but preferably being covered with a small piece of rubber tubing 74. The card separator 62 is normally held against the rubber covered stop lug 72 by a light tension coil spring 76, one end of which is secured to the separator 62 and the other end of which is anchored to an end 78 formed at the lower end of the bracket 66. The end of the separator 62 projects through a slot 80 formed in the rail 58 and has a shoulder 82 which lies substantially in the plane of the inclined portion of the rail 58 when the separator is in normal position, as shown in Fig. 3. A card stop 84 projects slightly above the inclined surface of the rail 58, the stop being of slightly lesser diameter at its base than at its outer extremity.

When, as indicated in Fig. 6, the picker thumb 30 slides more than one card from the stack, the inclined rails 58, 60 will tend to separate the topmost card from the remaining cards beneath which may have been displaced with the topmost card. Occasionally, however, the second card, and, very rarely, the second and third cards, will adhere to the topmost card and would slide up the incline with the topmost card, were it not for the card separator. The topmost card will in every instance be a short distance in advance of the next lower card or cards and will be the first to engage the end of the card separator 62. As the latter is engaged, it swings upwardly and its shoulder 82 engages and raises the leading edge of the topmost card above the card stop 84. The second, and very rarely the third, card will, however, not be raised by the card separator 62 and will be arrested by the card stop 84. After the topmost card has thus been separated from the remaining cards, it will be slid upwardly until its leading edge engages the guard rail 86 and moves successively from the position indicated in dotted lines at 88, in Fig. 7, to the position in which the card is shown in full lines in said figure. It will be noted that in Fig. 7 the roller 26 has commenced rolling up an incline 90 formed on the inner rail 28, and the picker thumb 30 has just been raised from contact with the card. The card will, however, continue movement, due to its momentum, until it is arrested by the spring finger stop 92, which may be secured to the guard rail 86. A single card will thus have been removed from the stack and placed in a predetermined position for engagement by the card pusher or carrier 40, 42. The latter, following the card picker thumb, will engage and convey the card removed from the stack around the track to one of the card receptacles S, W, N, E.

After the card picker thumb has moved beyond the position in which it is shown in Fig. 7, means are provided to restore any cards which may have been displaced from the stack in the box 46 to their normal, proper superimposition. This

means comprises a deck wire 94 which is suitably mounted for rotation and has an upwardly extending arm 96 formed integrally therewith. The opposite end of the deck wire 94 has a short crank arm 98 formed thereon, the arm 98 being adapted periodically to be contacted by a lug 100 projecting from the bottom of the turntable 16. The deck wire 94 is held in the position in which it is shown in Figs. 5 and 6 by a torsion spring 102. When, however, the lug 100 engages the crank arm 98 of the deck wire, the latter is swung from the full line position, shown in Fig. 7, to the position in which it is shown in dotted lines in said figure, thereby repositioning the cards one above the other in regular stack formation.

In operation, the turntable 16 rotates continuously during a dealing operation and the picker thumb 30 removes the cards from the stack in the deck box 46, one at a time, in the manner previously described. The inclined rails 58, 60, together with the card separator 62 and card stop 84, are effective to prevent all but the topmost card of the deck from being "picked up" by the picker thumb 30. After removal of each successive card from the deck, the remaining cards are restored to their normal stacked position by the deck wire 96.

The principles of the card separating mechanism herein disclosed may, of course, readily be employed in devices other than a card dealing apparatus and may be embodied in various forms. I therefore desire the accompanying claims to be construed to include all such equivalents, modifications and variations as may be apparent to those skilled in the art.

What I claim and desire to secure by Letters Patent is:

1. In a card feeding device, the combination of means for holding a stack of playing cards, a friction device engageable with the topmost card of the stack for sliding it therefrom, an inclined rail located adjacent said means and positioned to be engaged by cards slid from the stack, a fixed card stop on said rail, and a card separator engageable by the leading edge of the foremost card and actuated thereby to guide the latter in a path over said stop.

2. In a device of the class described, the combination of means for frictionally feeding cards from a stack and means for separating the topmost card from other cards which may have adhered thereto, said means comprising a fixed stop, and a member engageable by the topmost card and operable thereby to lift it over said stop.

3. In a device of the class described, the combination of a card picker mechanism, said mechanism including an inclined rail, a rigid stop secured to said rail, and a pivoted card separator arm carried by said rail and adapted to be engaged and operated by the topmost card fed from said stack thereby to lift said topmost card over said fixed stop, said fixed stop being effective to arrest cards adhering to the topmost card.

4. A card separating device comprising, a rail, a card stop fixed to said rail, and a movable card separator projecting above the level of said rail and adapted to be engaged and operated by the leading card to raise the latter over said stop but to permit any cards adhering to the topmost card to be arrested by said stop.

5. In a device of the class described, the combination of a rail, a bracket fixedly secured thereto, a notched arm pivoted to said bracket and having an extension projecting above the surface of said rail, a stop fixed to said rail ad-

- 5 jacent said arm, and card feeding mechanism
adapted to move cards along said rail, said mech-
anism being arranged to cause engagement of
said arm by the foremost only of a plurality of
cards, whereby said arm will be actuated by and
raise the foremost card over said stop, said stop
being effective to arrest movement of any cards
adhering to the foremost card. 80
- 10 6. A card separator mechanism comprising, a
guideway for cards, friction contact means for
sliding the topmost card from a stack and moving
it along said guideway, a fixed card stop on
said guideway adapted to arrest movement of all
but the topmost card of the stack, and a card
separator mechanism arranged to be engaged by
the leading edge of the topmost card and actuated
thereby to move the latter through a path clearing
said stop. 85
- 15 7. A device for preventing the feeding of more
than one card at a time along a track, comprising
a stop positioned in the normal path of the cards
along said track, and card actuated means for
rendering said stop ineffective for the foremost
of a group of cards being fed along said track. 90
- 20 8. A device for preventing the feeding of more
than one card at a time along a track, compris- 95
- 25 ing a stop positioned in the normal path of the cards
along the track, and a separator element
positioned to be engaged by the leading edge of
the foremost of a group of cards being moved
along the track and operable by the card to de-
flect the card past said stop, said stop serving to
arrest the remaining cards of the group. 100
- 30 9. A card separator mechanism comprising, a
guideway for cards, a card stop secured to said
guideway and adapted to arrest movement of all
but the foremost of a group of cards moved
along said guideway, and a card separator ar-
ranged to be engaged by the leading edge of the
foremost card and actuated thereby to deflect
the latter through a path clearing said stop. 105
- 35 10. In a device of the class described, the com-
bination of means for feeding cards from a stack
and means for separating the topmost card from
other cards which may have adhered thereto,
said means comprising a stop, and a member
engageable by the topmost card and operated
thereby to deflect the topmost card past said
stop, said stop being effective to arrest cards re-
moved from the stack with the topmost card. 110
